UNITED STATES PATENT OFFICE.

GEORGE A. PAFF, OF SHARON, PENNSYLVANIA, ASSIGNOR TO THE AMERICAN STEEL & WIRE COMPANY, OF WORCESTER, MASSACHUSETTS, A CORPORATION OF NEW JERSEY.

WIRE-DRAWING APPARATUS.

No. 840,707.

Specification of Letters Patent.

Patented Jan. 8, 1907.

Application filed November 3, 1905. Serial No. 285,678.

To all whom it may concern:

Be it known that I, GEORGE A. PAFF, of Sharon, Mercer county, Pennsylvania, have invented a new and useful Improvement in 5 Wire-Drawing Apparatus, of which the following is a full, clear, and exact description, reference being had to the accompanying drawings, forming part of this specification, in which—

10 Figure 1 is a side elevation, partly in section, of wire-drawing apparatus embodying the invention. Fig. 2 is a view, partly in side elevation and partly in vertical section, of the parts constituting the invention. Fig. 15 Fig. 3 is a detail view of the sheave-lifting device. Fig. 4 is a top plan view of the sheave. Fig. 5 is a perspective view of the clutch, and Fig. 6 is a detail view of a suitable wire-clamping device.

20 In the operation of reducing wire by drawing it through a die it is necessary to provide the drawing-frame with a draw-out arrangement so constructed that a tong or grip may be brought very closely to the drawing-die and pinch the pointed end of the wire protruding therethrough to pull a sufficient length of the wire through the die to enable the operator to fasten its end to the drawing-block. Various means have heretofore been 25 employed for this purpose, but such means have been more or less complicated and cumbersome and arranged in a manner to interfere with the operator.

The object of my invention is to provide 35 means of very simple character applied to the drawing-block and its driving-shaft by means of which the necessary amount of wire can be drawn through the die to permit its attachment to such block and which are so 40 constructed and arranged as to be out of the way of the operator and to rapidly and effectively accomplish the desired result.

The invention consists in a novel construction and arrangement and combination of 45 parts, all substantially as hereinafter described, and pointed out in the appended claims.

In the drawings the numerals 2, 3, and 4 50 designate three drawing-blocks of the usual character mounted upon driving-shafts 5 in

the usual manner in a bench or table 6. In practice it is usual to mount a considerable number of these blocks upon a long bench or table. Fig. 1 shows three of such blocks, the table or bench being broken away. The 55 shafts 5 are driven by any suitable or usual driving-gear 7.

8 designates clutch-hubs, one of which is mounted on a squared portion 9 of each shaft 5 to revolve therewith. These hubs 60 are similar to the hubs generally employed for driving the drawing-blocks with the exception that they are provided with the depending lugs 10 for the purpose hereinafter described. The blocks 3 are loosely mounted on the shafts 5 and are engaged with and disengaged from the clutches 8 by any usual or suitable treadle-lever mechanism 11, as indicated in dotted lines at the upper left-hand portion of Fig. 1. As this mechanism 70 is common, I have not shown it applied to the other blocks, and it is unnecessary to describe it in detail.

12 designates a grooved sheave which is loosely mounted on a depending boss 8^a of 75 the clutch member 8 and has on its upper surface the lugs or abutments 14, which are designed to be engaged by the depending lugs 10 of such clutch member to rotatably connect the sheave with the shaft 5 when the 80 sheave is moved vertically on the boss 8^a. For the purpose of raising the sheave the treadle-lever 15 is provided, actuated by a push-rod 16 and carrying lifting-rods 17, which are adapted to engage the under side 85 of the sheave at substantially diametrically opposite points. In order to get around the shaft 5 and to enable the push-rods 17 to get a central lift upon the sheave, these rods are connected to a yoke 18, which extends around 90 the shaft 5, as shown in Fig. 3, and is connected to the lever 15 by a rod 16'.

Formed on the upper surface of the sheave 12 are two vertical projecting diametrically opposite lugs 19 and 20, having each a squared shoulder 21 and an inclined upper surface leading up to such shoulder, the lug 20 being somewhat shorter than the lug 19, as shown in Fig. 2, and at a greater distance from the center of the sheave than the lug 100

19. Secured to the bench or table 6 are two fixed brackets 23, which have portions 24 overhanging the peripheral portion of the sheave in the manner shown in Fig. 2.

5 25 designates any usual or suitable wire-clamping device attached to the drawing-blocks.

26 is a rope or cable, one of which is attached to each of the sheaves 12 and which 10 has at its free end a suitable wire-clamping device 27, (one form of which is shown in detail in Fig. 6.)

28 designates the usual vises or diaphragms in which the drawing-dies are held, and 29 15 indicates the wire to be drawn.

Each of the drawing-blocks is provided with the clutch and sheave arrangement above described, that upon each block being arranged to make the preliminary draw of wire 20 for the next preceding block. Thus in Fig. 1 the arrangement of the block 3 is shown in position to make the draw for the block 2, while the block 4 is illustrated as having a drawn wire coiled about it.

25 The operation is as follows: The drawing-blocks are lowered into driving engagement with the shaft 5 by means of the treadle mechanism 11 or in any other usual or suitable manner. When it is desired to make a 30 preliminary draw, the operator places his foot upon the push-rod 16, thereby actuating the lever 15 to raise the push-rods 17 and lift the sheave 12 into position where it would be engaged by the depending lugs 10 of the revolving clutch member 8, the wire to be drawn having been gripped close to the drawing-die by means of the gripping device 27 at the end of the rope 26. The sheave 12 is now rotated, the shorter projection 20 there- 35 on passing underneath the overhanging projections 24 of the brackets 23, while the longer projection, being nearer the center, escapes the first of such projections on its first half-revolution. When, however, the 40 sheave has made substantially a complete revolution, which draws a sufficient length of wire for attachment to the drawing-block, the projection 19 will engage with one of the overhanging portions 24. The cam-surfaces 45 of the projections 19 and 20 riding against the portions 24 cause the sheave to be forced downwardly out of driving engagement with the clutch member, thereby stopping the rotation of the sheave. The drawn portion of 50 the wire is then attached to the drawing-block and the operation of drawing commences. Inasmuch as the projections 19 and 20 are arranged diametrically opposite to each other it will be seen that their cam- 55 action will effect a true vertical movement of the sheave without causing the latter to bind on the boss of the clutch member.

60 The advantages of my invention result from the simple and effective construction

and arrangement of the parts, the ease with 65 which they may be operated without in any way interfering with the operator, and also from the fact that there results but little waste in wire, owing to the fact that only the immediate end portion thereof engaged by 70 the grip 27 is injured by the drawing operation.

By mounting the sheave upon the boss of the clutch member and around the shaft which drives the drawing-block I am able to 75 dispense with all intermediate gearing for driving the clutch member. The sheave is in this manner also utilized to form one member of the clutch and to carry the cam and stop devices. This greatly simplifies the construction and arrangement of the sheave. It furthermore brings the sheave into parallel relation with the drawing-block, so that it may exert a direct pull upon the wire without the use of intermediate pulleys. 80

Many changes may be made in the details of construction and arrangement of the parts without departing from my invention, since

What I claim is—

1. In wire-drawing apparatus, the combination with a drawing-block having a clutch member, of a sheave loosely mounted on the same shaft with the drawing-block and adapted to be moved into and out of engagement with such clutch member, and a wire-gripping device attached to the sheave; substantially as described. 90

2. In wire-drawing apparatus, the combination with a drawing-block having a clutch member, of a wire-drawing sheave loosely mounted on the same shaft with the drawing-block and means for moving such sheave into driving engagement with the clutch member, and means for disengaging the sheave from the clutch member after substantially a complete revolution of the sheave; substantially as described. 100

3. In wire-drawing apparatus, the combination with a drawing-block, a wire-drawing sheave loosely mounted on the same shaft with the drawing-block and means for effecting a rotating engagement between the sheave and block, and means for automatically disengaging the sheave from the block; substantially as described. 110

4. In wire-drawing apparatus, the combination with a drawing-block, of a rotating loosely-mounted wire-drawing sheave loosely mounted on the same shaft with the drawing-block and actuating means for moving said sheave into and out of driving engagement with the block; and cam means for automatically effecting the disengagement of the sheave; substantially as described. 120

5. In wire-drawing apparatus, the combination of a drawing-block having a clutch member, a wire-drawing sheave mounted on said clutch member and adapted to be moved

into and out of driving engagement therewith, means for effecting such engagement, said sheave having cams thereon, and relatively fixed means arranged to engage the 5 cams to effect the disengagement of the sheave and clutch member at a predetermined time; substantially as described.

In testimony whereof I have hereunto set my hand.

GEO. A. PAFF.
